UNITED STATES PATENT OFFICE.

ERNEST L. PATTEN, OF NEW HAVEN, CONNECTICUT, ASSIGNOR TO L. CANDEE & COMPANY, OF NEW HAVEN, CONNECTICUT, A CORPORATION OF CONNECTICUT.

BLANK-CUTTING MACHINE.

Application filed July 22, 1925. Serial No. 45,177.

This invention relates to a blank cutting machine, more particularly to a machine for dieing out blanks, such as rubber shoe uppers, from sheet stock.

5 In the making of rubber footwear such as rubber overshoes it has been customary in forming the blank for the shoe upper from sheet stock to perform this operation manually, the operator either running a knife around a raised bead on the stock outlining the upper, or disposing a pattern on the stock and passing a knife around the edge of the pattern, or alternatively using a die in the shape of the desired blank and after placing 10 this upon the stock striking it with a mallet. Such operations can only be performed relatively slowly, and in the case where the calendered stock is provided with preformed raised beads outlining the upper edge of the 15 uppers the operation requires a careful placing of the die or pattern and manipulation of the knife in order that this bead may not be cut through.

An object of my invention is to provide a 20 machine for automatically dieing out blanks, such as rubber shoe uppers, from sheet stock. Another object is to provide a machine for dieing out blanks in registry with predetermined outlines on the sheet stock. Still another object is to die out blanks in registry with such outlines from a continuously moving sheet stock. A further object is to provide an improved safety device for preventing 25 injury to the operator by the dies.

The machine comprises broadly a reciprocable die, means for intermittently raising the die and holding it in raised position, means governed by the stock passing beneath the die for releasing it, and means actuated 30 by the die in its operative stroke for assisting its return stroke. It also comprises an improved safety device for preventing injury to an operator by the die.

For a detailed disclosure of the nature and 35 objects of the invention reference is had to the accompanying specification and drawings, in which latter,

Fig. 1 is a front elevation of the machine;

Fig. 2 is a side elevation;

50 Fig. 3 is a front elevation on an enlarged scale of the left-hand half of Figure 1, with parts broken away;

Fig. 4 is a part transverse vertical section through Figure 3 with the die omitted;

Fig. 5 is an enlarged perspective of a trip switch;

Fig. 6 is an enlarged section partly broken away through the safety device;

Fig. 7 is a perspective of the inverted die;

Fig. 8 is a perspective of a detail.

Referring to the drawings the numeral 1 designates the main frame of the machine provided with a work bed 2 across which is movable a stock conveyor 3. In the present instance the machine is driven by an electric motor 4, the pulley 5 of which through the belt 6 is connected to the pulley 7 on the main shaft 8 of the machine. Adjacent each end of the main shaft a pinion 9 is secured, each of which engages a gear 10 loosely mounted on a shaft 11, and each gear shaft may be coupled to its gear 10 by means of a common form of clutch 12, each clutch also being provided with a brake mechanism 13 for stopping the shaft 11 when the clutch is disengaged. As shown in Figure 1 the shafts 11 are in alignment but independent of each other, and each shaft is adapted to drive a separate die mechanism. It is, of course, obvious that if desired only one die may be used in the machine, and since both of the die mechanisms are identical but one of them will be described.

In the upper part of the frame adjacent the front and back of the frame 1 tracks 14 are provided upon which run rollers or wheels 15 carrying a drop head 16. This head is provided with a vertical slideway 17 in which reciprocates a slide 18 carrying at its lower end a die head 19 with which is connected by a dove-tailed joint 20 the die 21. This die (Figure 7) comprises a substantially rectangular frame 22 within which are disposed complementary blocks 23, 24, 25 and 26 interfitting in such manner as to hold between them a die blade 27 formed in the outline of a shoe upper. The blocks form substantially a rectangular figure, two sides of which are in contact with the frame 22 while disposed against the other two sides are retaining strips 28 and 28' which are spaced from the frame 22, and in such space are disposed a plurality of quoins 29 which are adapted to be tightened by keys 30 to rigidly hold the assembly in the frame 22. An elongated slot 31 is provided between the blocks 26 for the reception of a stock contacting device or trip to be later described.

The upper end of the slide 18 is forked

as shown at 32 (Figures 3 and 4) and disposed in the forks is a cam roller 33 which is adapted to be actuated by a lifting cam 34 to raise the slide 18, die head 19, and die 21. 3 This cam is slidably keyed to the shaft 11 and as shown in Figure 4 is slotted or grooved along a portion of its periphery at 35, this slot being provided in order to allow the cam to clear a hook 36. This hook is adapted 10 to receive and retain the cam roller 33 when the latter is elevated to thereby maintain the die and its slide in elevated position. The hook is formed at the lower end of a bell crank 37 pivotally mounted in the frame, the 15 hook being normally urged to the right as shown in Figure 4 by a coil spring 38 surrounding its pivot. The other end of the bell crank 38 is connected to a pull rod 39 operable by a solenoid 40 (Figure 2). 20 This solenoid is operable by the trip mechanism shown in detail in Figure 5. This mechanism comprises a bracket 41 attached to the lower side of the drop head 16, the bracket being provided interiorly with the 25 slideways 42, on which is movable a slide 43, the slide carrying trip mechanism to be later described. The slide may be actuated by the screw rod 44 provided with a knob 45 (Fig. 4) this rod being threaded in a boss 46 on 30 the bracket 41, the inner end of the rod being rotatable in the slide 43 and connected thereto by the head 47. Projecting downwardly from the slide 43 is a supporting bar 48, in the lower end of which is pivotally mounted 35 a contact arm 49. The lower end of this arm extends to a point closely adjacent the stock 50 resting on the conveyor 3, so as to just clear the stock itself but in position to contact with the slightly elevated bead 51 out- 40 lining the upper edge of an upper. Projecting from the contact arm 49 is an arm 52 upon which rests a push rod 53, the upper end of the push rod being adapted to actuate a spring contact 54 and move it into circuit closing engagement with the spring contact 55. Leading from the contacts 54 and 45 55 are wires 56 connecting the contacts with the solenoid 40 and a suitable source of current. 50 When the contact arm 49 is moved to actuate the solenoid 40 and withdraw the hook 36 from the cam roller 33 the slide 18 and die 21 drop on the stock to die out a blank, and as it is desirable to keep the stock continuously moving it is essential that the die be withdrawn as rapidly as possible. To accomplish this the slide 18 is provided with a projecting lug 57 (Figure 4) which in the downward movement of the slide engages 55 one end of a lever arm 58, the other end of which is forked and presses against a washer 59 bearing against a coil spring 60 disposed on the rod 61. In this manner it will be seen that as the die falls the coil spring 60 is suddenly compressed and the reaction of this

spring assists in causing a rapid rebound of the die.

In order to catch the die mechanism on its rebound and again elevate it the following mechanism is provided. Projecting from the die head 19 is a lug 62 in which is adjustably secured a contact screw 63, the end of this screw in the fall of the die engaging an arm 64 secured on one end of a rock shaft 65, while secured on the opposite end of the rock shaft is another arm 66 which is connected by a link 67 with a bell crank lever 68 for actuating the clutch 12, to operatively connect the gear 10 and shaft 11. Springs 69 secured to the frame 1 and arm 66 normally 70 maintain the arm in elevated position and the clutch inoperative. When the arm 66 is operated, however, by the fall of the die, the clutch is operated momentarily or for a sufficient period of time to cause one rotation 75 of the shaft 11, by which time the springs 69 have rendered the clutch inoperative again and caused the application of the brake 13 to stop the shaft 11 at the end of a complete revolution. During this revolution the cam 80 85 90 95 100 105 110 115 120 125 130

As before stated the operation of the second die is identical with that of the first, and due to variations of the position of the stock 95 on the conveyor belt or variations in the lateral spacing of the beads on the stock it is desirable to adjust the die mechanisms laterally. In order to accomplish this a hand wheel 70 is mounted at the side of the frame 100 1 on a hollow shaft 71 carrying at its opposite end a sprocket 72, this sprocket being connected by the chain 73 with a sprocket 74, the chain also running over an intermediate take up sprocket 75. The sprocket 74 is secured on the end of an adjusting screw 76 which is stationarily and rotatably mounted in the frame (Figures 2 and 3). The adjusting screw 76 is threadedly connected to a nut 77 mounted in a bracket 78 projecting from the head 16, and it will be seen that by movement of the hand wheel 70 the head 16 and associated parts may be laterally moved on the tracks 14. A second hand wheel 79 is provided with a shaft 80 extending through the hollow shaft 71 and across to the opposite side of the machine where the shaft is provided with a sprocket 81 adapted through connections similar to those just described to laterally move the right-hand head 16.

In order to prevent injury to the operator during the use of the dies a guard 82 is provided which surrounds the dies, and each side of the guard is connected to a slide 83 movable in the frame of the machine (Figure 6). Attached to the guard 82 are cables 84 which pass over pulleys 85 and are connected to counter weights 86, to hold the guard in elevated position when raised. Disposed in the frame is a switch 87 provided with a switch

arm 88, the switch being suitably wired for stopping or starting the motor 4 of the machine. This switch arm engages an opening in a latch 89 slideable in the frame, the latch when in the position shown in Figure 6 extending over the slide 83 so as to prevent raising of the guard, and when thus disposed the switch arm 88 is in a position to close the switch and permit motor 4 to operate. As soon as the latch 89 is withdrawn, however, the switch arm 88 is thrown over in position to cut off the current and the motor is stopped. At this time the guard may be raised. As an additional safeguard it is pointed out that when the slide 83 and guard are raised the slide prevents inward movement of the latch 89, hence the latch cannot be moved to close the switch 87 while the guard is raised. As the die is somewhat heavy a roll 90 is provided at one side of the machine to permit the ready removal of the die when it is to be changed or repaired, the die being slid out over this roll as it is removed.

In operation the stock coming from the calender after being preliminarily cooled and dusted is fed on the conveyor 3 and into the machine which is then started. As the stock feeds through the machine the contact arm 49, which projects through the opening 31 in the die, is engaged by a bead 51 on the stock, thereby operating the solenoid 40 to release the die, which falls in position such that the inner portion of its blade cuts exactly around the inner edge of the bead 51. The die assisted by the spring 60 then rebounds, and as before pointed out, in its fall it has actuated the arm 66 to clutch the gear 10 and shaft 11 together to rotate the shaft and in the rotation of shaft 11 the cam 34 operates upon the cam roller 33 to lift the die until the cam roller is engaged by the hook 36. Upon the contacting of the arm 49 with the next succeeding bead 51 the foregoing operations are repeated. By turning the knob 45 the position of the contact arm 49 may be varied in the slot 31 of the die so that the fall of the die will be properly timed to cut exactly around the bead 51. Due to the lateral adjustment of the entire die mechanism and the interchangeability of the dies changes may be quickly made for different sizes of uppers and for different spacings thereof on the sheet stock. By reason of the rapid rebound of the die after cutting there is no occasion for the stopping of the stock during a dieing operation and the speed of the machine is therefore increased. By reason of the guard construction it is impossible for the operator to lift the guard while the machine is in operation, and once having lifted it the machine cannot be put in operation until the guard is again lowered. By the use of my machine blanks for shoe uppers can be rapidly and accurately die'd out with great saving in time and labor. While in the spe-

cific example shown the invention is applied to the dieing out of rubber shoe uppers, it is evident that it is capable of much wider application and may be used generally for dieing out blanks from sheet materials. It is therefore not desired that the invention be limited otherwise than as set forth in the appended claims.

Having thus described my invention, what I claim and desire to protect by Letters Patent is:

1. A machine for dieing out blanks from sheet stock comprising a vertically movable die, means for intermittently raising and holding the die in elevated position, a conveyor for continuously supporting the stock during its feeding and dieing, and means actuated by the stock fed to the die for releasing the die at each blanking operation.

2. A machine for dieing out blanks from sheet stock comprising a vertically movable die, means for intermittently raising the die, a trip for holding the die in raised position, and means operable by the stock for actuating the trip to release the die at each blanking operation.

3. A machine for dieing out blanks from sheet stock comprising a vertically movable die, rotary means for intermittently raising the die, a spring pressed trip for holding the die in raised position, and means operable by portions of the stock when in predetermined relation to the die for actuating said trip at each blanking operation.

4. A machine for dieing out blanks from sheet stock comprising a vertically movable die, means for intermittently raising the die, a trip for holding the die in raised position, means operable by portions of the stock for releasing the trip at each blanking operation, and means for varying the timing of the trip release.

5. A machine for dieing out blanks from sheet stock comprising a vertically movable die, means for intermittently raising the die, a trip for holding the die in raised position, means operable by portions of the stock for actuating the trip at each blanking operation, and means for varying the position of said trip actuating means with respect to the die.

6. A machine for dieing out blanks from sheet stock comprising a vertically movable die, means for intermittently raising the die, a trip adapted to engage the die when raised, a solenoid for actuating said trip to release the die, and contact means operable by portions of the stock for rendering said solenoid operative at each blanking operation.

7. A machine for dieing out blanks from sheet stock comprising a vertically movable die, means for intermittently raising and holding the die, means for continuously supporting and feeding beneath the die a sheet of stock having raised portions thereon, and

- adjustable contact means disposed within the outline of the die and actuated by said raised portions for intermittently releasing the die.
8. A machine for dieing out blanks from sheet stock comprising a vertically movable die, means for intermittently raising and holding the die, means for feeding beneath the die a sheet of stock having a raised outline thereon, and means operable by said outline when within the outline of the die for releasing the latter.
9. A machine for dieing out blanks from sheet stock comprising a gravity actuated die, intermittently operable means for raising and holding the same, means governed by stock fed to the die for intermittently releasing the latter, and means actuated by the die in falling for putting into operation said die raising means.
- 20 10. A machine for dieing out blanks from sheet stock comprising a gravity actuated die, means for intermittently raising and holding the same including a cam and operating means therefor, means governed by stock fed to the die for intermittently releasing the die, and means actuated by the die in falling for operatively connecting said cam and its operating means.
11. A machine for dieing out blanks from sheet stock comprising a gravity actuated die, means for intermittently raising and holding the same, means governed by stock fed to the die for intermittently releasing the latter, means for assisting the rebound of the die after falling, and means actuated by the die for rendering operative said die raising means.
12. A machine for dieing out blanks from sheet stock comprising means for feeding a sheet of stock, spaced vertically movable dies disposed thereabove, means for varying the spacing of the dies, means for intermittently raising and holding the dies, and means actuated by portions of the stock for releasing the dies at each blanking operation.
- 45 13. A machine for dieing out blanks from sheet stock comprising means for continuously feeding a sheet of stock, spaced vertically movable dies disposed thereabove, means for varying the spacing of the dies, means for intermittently raising the dies, trip means for holding the dies in raised position, and means actuated by portions of the stock for releasing said trip means at each blanking operation.
- 55 14. A machine for dieing out blanks from sheet stock comprising means for continuously feeding a sheet of stock, spaced vertically movable dies disposed thereabove,
- means for varying the spacing of the dies, 60 means for intermittently raising the dies, trip means for holding the dies in raised position, means actuated by portions of the stock for releasing said trip means at each blanking operation, and means for varying 65 the timing of said last means.
15. A machine for dieing out blanks from sheet stock comprising driving means, a vertically movable die, a cam for elevating the die, clutch mechanism for operatively connecting the cam to the driving means, means for holding the die in elevated position, means actuated by stock fed into the machine for releasing the die, and means actuated by the die for operating said clutch mechanism. 75
16. A machine for dieing out blanks from sheet rubber stock comprising spaced gravity actuated dies, means for elevating the dies, means for holding the dies in elevated position, means for feeding to the dies a sheet stock having spaced raised outlines thereon, means governed by said outlines for releasing the dies at predetermined intervals, and means for varying the spacing of the dies and the timing of the die releasing means in accordance with the spacing of the outlines on the stock. 80
17. A machine for dieing out blanks from sheet stock comprising a vertically movable die, means for elevating the die, a trip for holding the die in elevated position, a solenoid for operating said trip, a switch for closing a circuit through said solenoid, said switch being adjustably mounted in predetermined relation to the die, and means for closing said switch operable by the stock at predetermined intervals. 85
18. A machine for dieing out blanks from sheet stock comprising a vertically movable die, means for raising the die, drive means, a clutch for operatively connecting said last two means, yielding means for rendering the clutch inoperative, and means actuated by the die in falling for rendering the clutch operative. 100
19. A machine for dieing out blanks from sheet stock comprising a continuously movable stock conveyor, a gravity actuated die cooperating therewith, means for raising and holding the die, means governed by the stock on the conveyor for releasing the die, and means for augmenting the rebound of the die from the conveyor after a blanking operation. 110

Signed at New Haven, county of New Haven, and State of Connecticut, this 16th day of July, 1925.

ERNEST L. PATTEN.
